UNITED STATES PATENT OFFICE.

JOHN K. MARTINKA AND ELIZI K. MARTINKA, OF NEW YORK, N. Y., ASSIGNEES OF
ONE-THIRD TO MARTIN TOMECEK, OF NEW YORK, N. Y.

DESIGN FOR AN EGG-TESTER.

57,988.

Specification for Design.

Patented May 24, 1921.

Application filed December 10, 1920. Serial No. 429,805. Term of patent 7 years.

To all whom it may concern:

Be it known that we, JOHN K. MARTINKA and ELIZI K. MARTINKA, citizens of Czechoslovakia, residing at New York, in the county of New York and State of New York, have invented a new, original, and ornamental Design for an Egg-Tester, of which the following is a specification, reference being had to the accompanying drawing, forming part thereof.

The figure is a view in perspective of an egg tester, showing our new design.

We claim:

The ornamental design for an egg tester, as shown.

JOHN K. MARTINKA.
ELIZI K. MARTINKA.
